UNITED STATES PATENT OFFICE.

EDWARD C. FOWLER, OF BRISTOL, CONNECTICUT, ASSIGNOR TO THE
BRISTOL BRASS AND CLOCK COMPANY, OF SAME PLACE.

ACETYLENE-GAS LAMP.

SPECIFICATION forming part of Letters Patent No. 661,511, dated November 13, 1900.

Application filed October 28, 1899. Serial No. 735,048. (No model.)

To all whom it may concern:

Be it known that I, EDWARD C. FOWLER, a citizen of the United States, residing in Bristol, in the county of Hartford and State of Connecticut, have invented certain new and useful Improvements in Acetylene-Gas Lamps, of which the following is a specification.

My invention relates to improvements in acetylene-gas lamps for vehicles; and the objects of my improvements are simplicity and economy in construction and convenience and efficiency of the article.

In the accompanying drawings, Figure 1 is a side elevation of my lamp, with a portion thereof near the bottom in sectional elevation. Fig. 2 is a front elevation of the same. Fig. 3 is a sectional view thereof on the line $\alpha\alpha$ of Fig. 2, but partly in elevation. Fig. 4 is a detached rear elevation of the back reflector ring. Fig. 5 is a central horizontal section, partly in plan view, of the back-reflector and adjacent parts of the lamp. Fig. 6 is a front elevation of the back reflector. Fig. 7 is a reverse plan view of the gas-chamber with the carbid-holder removed, and Fig. 8 is a plan view of the base of the gas-chamber.

The complete lamp is substantially T-shaped in side view. A designates a horizontal cylinder, which is surmounted by a dome 9. Under the dome and near the middle of the said cylinder are the back-reflector ring 10 and back reflector 11, in front of which is the burner-chamber, having the gas-burner 12, cone-reflector 13, lens 14, and lens-ring 15, which are mainly of an ordinary construction and need not be specifically described. In the rear end of the horizontal cylinder A is the upper or main water-chamber 16, the same being provided at the top with a filling-orifice and cap 17. The sides of the said horizontal cylinder are left open just back of the back-reflector ring 10, so that the back reflector 11 may be inserted and removed through one of said openings. The said reflector is provided with a handle 18 and is of the usual concave form in its middle portion, while its top and bottom edges are left straight, as shown in Fig. 6, to enable the said reflector to be guided by the ways 19 on the back of the back reflector-ring. A spring 20 is secured by one end to the front wall of

the main water-chamber 16 and projects into the path of the back reflector, so as to extend over and press upon the conical side of its central portion, as shown in Fig. 5, whereby the said reflector can at any time be readily and conveniently removed for cleaning and readily replaced.

Underneath the horizontal cylinder A is an upright or vertically-arranged portion, at the upper end of which is a ring-frame 21, within which is a supplemental water-chamber 22, that communicates with the main water-chamber 16 by means of the tube or pipe 23. Underneath the supplemental water-chamber and concentric thereto is the gas-chamber 24, with a removable base 25. A suitable connecting pipe or tube 26 leads from the interior of the gas-chamber 24 through the water-chamber 22 to the burner 12.

In the center of the supplemental water-chamber 22 is a vertical valve-socket 27, Fig. 3, with the central bore or orifice through it threaded from end to end and with a transverse opening or openings 28 near the bottom of the water-chamber, that extend through to its central bore. The tubular plug 29, the upper end of which serves as a valve-seat, is exteriorly threaded and is screwed into the lower end of the valve-socket 27, while the conical valve 30 is correspondingly threaded and is screwed into the upper end of said socket, with its upper end projecting above the chamber 22 and provided with a resilient handle 38, (represented as removed from Fig. 3,) that extends to the outer part of the ring-frame 21 and bears upon the holding-notches 31, formed in the said frame, whereby moving the said handle from notch to notch or over several notches will partially rotate the valve to screw it either out or in, as may be desired. A rubber or other packing 32 may be placed around the upper end of the valve 30, as shown in Fig. 3. As shown in Fig. 1, the extreme right-hand one of the notches 31 represents the closed portion of the valve or what I may term its "zero-notch." In assembling the parts the valve is screwed in and its handle inserted and then turned to zero. Then the tubular plug 29, the upper end of which forms the valve-seat, is screwed in until it presses against the valve, so as to close it tightly. In this way it is very easy to ad-

just the parts so as to insure a closed valve when the handle is in the zero-notch. The valve is provided with a reduced neck 33 between its conical end and its body in order 5 that the water may always have free access to the said conical end. The tubular plug 29, like all other tubes, has a longitudinal passage 50 therethrough.

The exterior of the gas-chamber 24, as 10 shown, is provided with a hood 34, having a skirt 35, and slightly above the bottom end 36 of said gas-chamber there are three cam- ledges 39, slightly separated at their con- fronting ends to form notches and all tapered 15 at one end 37, as shown in Fig. 1. The flanged base 25 shuts over the outer sides of the cam-ledges 39 and is provided on the in- 20 inner side of its flange with pins or projections 40, (one of which is shown in section in Fig. 21,) that pass through the spaces or notches be- 25 tween the cam-ledges and over the tapering ends of said ledges, whereby by turning the 30 base to force the pins up the taper of said ledges the base may be very firmly secured 35 to the lower end of the gas-chamber; but in- 40 stead of having the bottom of the base di- rectly engage the bottom end 36 of the gas- 45 chamber I form an inner central projection or hub 41 on said base, and on the said projec- 50 tion I place a disk 42 and suitable packing 55 43 for pressing against said bottom end 36, whereby the disk and packing may rock and 60 tip to adjust themselves to the said bottom end, and, further, the said disk and packing 65 may be held against rotation by the friction 70 of said bottom end while the base is par- 75 tially rotated to tighten it in place, thereby 80 not only insuring a tight joint, but also mak- 85 ing a joint that is readily detachable, al- 90 though it may become clogged. In other 95 words, if the disk and bottom end of the gas- 100 chamber become stuck together by gas or cor- 105 rosion the base can easily be turned for de- 110 taching without turning the disk, because 115 there is so little friction between the central 120 projection 41 of the said base and the said 125 disk. The carbid-holder 45, Fig. 3, that is 130 placed within the gas-chamber, is of an ordi- 135 nary construction, and it is held against rat- 140 tling by means of the spring 44, while at the 145 same time the spring will yield and permit 150 the carbid-holder to expand. This ordinary 155 carbid-holder consists of the main body or 160 holder 45, a removable flanged bottom 46, 165 that shuts over the lower end of the carbid- 170 holder telescopic fashion to permit expan- 175 sion, and a central tube 47 to receive the 180 lower end of the tubular plug 29, the lower 185 end of the said tube being perforated or slit, 190 as at 48, to allow the water to flow into the 195 carbid-holder. The gas passes out through 200 two or more small holes 49 in the top of the 205 carbid-holder and then through the tube 210 to the burner 12.

65 It is apparent that some changes from the specific construction herein disclosed may be made, and therefore I do not wish to be un-

derstood as limiting myself to the precise form of construction shown and described, but desire the liberty to make such changes 70 in working my invention as may fairly come within the spirit and scope of the same.

I claim as my invention—

1. An acetylene-gas lamp, substantially T- shaped in side view having in combination 75 the horizontal cylinder provided with the burner-chamber at one end and the main wa- ter-chamber at the other, the upright cylind- 80 rical portion containing the supplemental wa- ter-chamber and gas-chamber, the said sup- 85 plemental water-chamber being arranged at the upper end of the said upright cylind- 90 rical portion underneath the said horizon- 95 tal cylinder above the said gas-chamber and having a communicating pipe connecting the 100 said water-chambers and a valve within the said supplemental water-chamber leading from the bottom thereof to the said gas-cham- 105 ber, substantially as described.

2. The combination of the water-chamber 90 22 with the valve-socket interiorly threaded and provided with a transverse opening com- 25 municating with said chamber, the valve 30 screwed into one end of the said socket, the 30 adjustable tubular plug the upper end of 95 which serves as a valve-seat screwed into the 100 other end of said socket and means for par- 105 tially rotating said valve and holding it in 110 the position into which it may be partially ro- 115 tated, substantially as described.

3. The combination of the water-chamber 120 22 with the valve-socket interiorly threaded and provided with an opening communicat- 125 ing with the said chamber, the valve 30 screwed into one end of the said socket, an 130 operating-handle projecting from the said 135 valve, a part rigidly mounted relatively to 140 the said water-chamber and provided with a 145 series of holding-notches for the said operat- 150 ing-handle, and an adjustable valve-seat for 155 the said valve whereby the said seat may be 160 adjusted to insure the tight closing of the 165 valve when the handle is placed in its zero- 170 notch, substantially as described.

4. In an acetylene-gas lamp, the combination 175 of the horizontal cylinder having the burner- 180 chamber at one end and the main water-cham- 185 ber at the other end, with the supplemental 190 water-chamber and gas-chamber arranged in 195 the form of a vertical cylindrical portion un- 200 derneath the said horizontal cylinder, the 205 said main and supplemental water-chambers 210 having a communicating pipe, a carbid-holder 215 within the gas-chamber having a water-inlet 220 and gas-outlets, a valve within the supple- 225 mental water-chamber for regulating the 230 flow of water to the carbid-holder and a pipe 235 leading from the gas-chamber to the burner- 240 chamber of the horizontal cylinder, substan- 245 tially as described.
